UNITED STATES PATENT OFFICE

JAMES C. ARTHUR, OF PLATTEVILLE, WISCONSIN

PLAYER PIANO

Application filed April 30, 1926. Serial No. 105,657.

This invention relates to player-pianos.

One object of the invention is to provide means in the form of a dynamic governor for controlling and regulating the low pressure or reduced air between the pneumatic stack and the pump or exhauster, which results in varying the dynamic force of the striking pneumatics, and at the same time governs the reduced air in such manner that one or 5 more notes used at the same time will result in striking of the corresponding hammers with equal dynamic force.

Another object of the invention is to provide a dynamic governor of the above character in which springs for providing resistance to the governor are entirely eliminated and automatically actuated pneumatically, operated means are utilized for providing the necessary resistance.

20 Still another object of the invention contemplates the provision of a system of the above character which is automatically actuated and controlled by the sheet of music in its passage over the tracker bar.

25 And a still further object of the invention is to provide a valve system for operating the dynamic governor wherein it is necessary to provide in the music roll only a short aperture which is utilized for actuating the valves

30 to admit atmospheric air to the governor, after which the aperture in the tracker bar is again closed by the music sheet while the valve remains in position to furnish atmospheric air to the governor, the valves being

35 cancelled or restored to their original position by means of a second and independent aperture in the music roll spaced the desired distance from the first aperture, depending upon the duration of the accented portion,

40 thereby eliminating the necessity of providing slots in the edges of the music roll which weakens the music sheet adjacent the edge and seriously interferes with proper tracking of the sheet over the tracker bar.

45 Other and further objects of the invention will more clearly appear from the description and claims hereinafter following.

In the drawings, Fig. 1 is a vertical, transverse, sectional view through a player-piano of conventional form showing the location

and connection of the expression apparatus contemplated by my invention. Fig. 2 is a side elevational view of the dynamic governor proper and the valve arrangement used in connection therewith, parts of the exterior wall of the governor being broken away to more clearly disclose the interior construction thereof. Fig. 3 is a top plan view of the dynamic governor and valve box. Fig. 4 is a transverse, vertical, sectional view through the governor substantially on the line 4—4 of Fig. 3. Fig. 5 is a fragmentary end elevation of the governor and valve box showing portions of the conduits leading to the pneumatic stack and to the pump. Fig. 6 is a fragmentary top plan view of the valve box. Fig. 7 is a vertical, sectional view of the invention substantially on the line 7—7 of Fig. 6, showing portions of the mechanism in elevation. Fig. 8 is a fragmentary side elevational view of the valve box. Fig. 9 is a vertical, transverse, sectional view through the valve box substantially on the line 9—9 of Fig. 6. Fig. 10 is a top plan view of the valve box with the cover removed therefrom. Fig. 11 is a top plan view of the valve box showing the arrangement of certain of the passages between the valves. Figure 12 is an enlarged sectional view of the invention similar to Figure 9. Figure 10 is a top plan view somewhat similar to Figure 12 and showing the ducts leading to the valve chambers. And Figure 13 is a longitudinal vertical sectional view corresponding substantially to the line 13—13 of Figure 12.

Referring first to Fig. 1 of the drawings, there is shown in conventional form a player-piano, which may be of any suitable type. Said piano ordinarily is provided with a pump 20, illustrated in the drawing as a manually operated bellows arrangement, but which usually is in the form of an electrically driven pump; and a pneumatic stack indicated at 21 which is usually divided so as to have two separate vent chambers and suction trunks leading to the pump 20, corresponding to the treble and bass portions of the piano, only one of said trunks being illustrated in the drawing and designated by the numeral 22. The tracker bar of the mechanism is

indicated at 23, and the music roll at 24. The piano action is indicated conventionally at 25. The mechanism thus far described is of a type ordinarily present in a large number of pianos which utilize various systems of operation.

The present invention has for its purpose the control of the piano action by the interposition in the trunk line 22, between the pump 20 and the stack 21, of a governing apparatus indicated broadly at A, which is automatically controlled by means of a valve arrangement indicated generally by the reference character B, which valve arrangement is automatically controlled by the passage of the music sheet 24 over the tracker bar 23. In this connection, it will be appreciated that although only one trunk line 22 is illustrated, and one governor with its associated parts shown, there will be provided two dynamic governors, one for the trunk line leading to the vent chamber of the treble portion of the pneumatic stack and one for the other trunk line leading to the vent chamber of the bass portion of the pneumatic stack.

The dynamic governor A comprises a stationary leaf 30 supported in any suitable manner, and said leaf is usually of box-like form having end walls 31—31 and side walls 32 and 32^a. The side wall 32 is preferably provided with two annular openings of the same diameter indicated by the reference characters 33 and 34, the aperture 34 communicating by means of the tube 35 with the pneumatic stack 21, while the opening 33 is connected by the tube 36 through trunk 22 with the pump 20. Pivoted secured to the forward edge of the stationary leaf 30 by means of a hinge 37 is the movable leaf 38 of the governor, said leaf being connected to the movable leaf by suitable air tight material commonly used in the player-piano art, as indicated at 39, which permits swinging movement of the movable leaf 38 with reference to the stationary leaf 30 as required. A knife valve 40 of well known form is pivotally connected at one end upon an eccentric 400 to the stationary leaf 30, as indicated, and is connected adjacent its other end with the movable leaf 38 as indicated at 41, said knife valve being adapted to control the size of the opening 33 dependent upon the movement of the movable leaf 38 of the governor so as to vary the passage of air from the pneumatic stack 21 to the pump 20.

In order to provide resistance against the collapse of the bellows formed by the stationary and movable leaves and the air tight cloth, when the air is reduced in the governor, there is provided an auxiliary bellows 42, which comprises a movable leaf hingedly connected adjacent one end to the movable leaf 38 of the governor, as indicated at 43, the movable leaf of the bellows 42 being flexibly connected to the leaf 38 of the governor by

suitable air tight fabric indicated at 44 while the same is rigidly connected to the stationary leaf 30 of the governor by a connection 300. The bellows 42 communicates with the governor by means of a small aperture 45, and hence the air in the governor and the bellows 42 will necessarily under ordinary conditions be at the same degree of pressure, and if the air in the governor is suddenly reduced, the collapse of the governor will be retarded or resisted by the slow passage of the air at a different pressure in the bellows 42 through the small opening 45, and when the pressure is again permitted to increase in the governor, the bellows 42 will automatically resume an equalized pressure. This arrangement provides the resistance to the collapse of the governor which can be effected by the utilization of suitable springs, but it will be appreciated that springs vary in tension and hence require frequent adjustment, whereas the pneumatic resistance just described is uniformly operable at all times. If any adjustment is required, the same can be made by varying the position of the eccentric pivot 400 of the knife valve.

With this arrangement, it will be appreciated that the governor automatically operates to furnish the required pressure in the pneumatic stack so that one or any number of notes will be struck with the same intensity, the governor automatically opening and closing as desired and hence operating the knife valve which opens and closes the aperture 33 the required amount.

Means are provided which control the movement of the movable leaf 38 of the governor in graduated degrees to effect variations of the dynamic force of the striking pneumatics, which are controlled from the tracker bar and operate upon the movable leaf of the governor to move the same independently of its automatic movement dependent upon the change in pressure in the pneumatic stack, the equal striking force of one or more pneumatics of course being at the same time taken care of by the variations in the movable leaf of the governor which are brought about by the variations of pressure in the pneumatic stack. Said means include what are in effect a plurality of small bellows or pneumatics graduated in size and herein-after termed power pneumatics, as the same move the movable leaf of the governor a certain extent when actuated. In the present embodiment of the invention, there are preferably provided power pneumatics 46, 47, 48, and 49. The power pneumatic 46 includes a leaf 50, which is rigidly connected to the stationary leaf 30 of the governor, preferably on the inner side thereof, and has a movable leaf 51 hingedly connected to the stationary leaf, the movable leaf 51 being connected to the stationary leaf 50 by suitable air tight fabric 52, the pneumatic 46 being sealed from the in-

terior of the bellows, and the same has an opening 53 to the exterior of the bellows, which opening leads to the valve arrangement hereinafter more particularly pointed out. The power pneumatic 47 is also secured to the stationary leaf of the governor and is of generally similar construction to the pneumatic 46, the pneumatic 47 being provided with an opening 54 extending to the valve box as hereinafter referred to. The only difference between the pneumatics 46 and 47 resides in making the pneumatic 47 of greater length as shown in order to provide increased capacity, so that when the pneumatic 47 is actuated, through suitable connections hereinafter referred to, the pneumatic 47 will move the movable leaf of the governor a somewhat greater extent than the pneumatic 46. The pneumatic 48 is similar to the pneumatics 46 and 47, except that the same is of still greater length, the pneumatic 49 being provided with an opening 55 leading to the valve arrangement. As many of these pneumatics graduated in size may be provided as will be deemed necessary, and although only three of the same are shown, it will be understood that any suitable number may be utilized. In addition to the smaller pneumatics 46, 47, and 48, there is provided a pneumatic 56 which is of relatively great size and capacity as shown, and shall be hereinafter known as the crescendo pneumatic, as operation of the same will effect a relatively great movement of the movable leaf of the governor, and hence have a marked effect upon the striking pneumatics. The crescendo pneumatic 56 has its upper leaf 57 connected to the movable leaf of each of the smaller pneumatics by means of the links 58, while the lower leaf 59 of said pneumatic is rigidly connected to the movable leaf of the governor. An aperture 60 communicates with the crescendo pneumatic and extends to the valve box in a manner hereinafter referred to.

All of the power pneumatics 46, 47, 48 and 49 are operated by a valve arrangement which for the sake of convenience is arranged in the valve box indicated at B. Said box houses a plurality of so-called primary valves corresponding in number to the number of power pneumatics associated with the governor. As best shown in Figs. 7 and 9, the valve box comprises a base portion 60^a which for the sake of convenience may be mounted upon the stationary leaf 30 of the governor. The base portion 60^a is provided with a plurality of pouch chambers 61, the chambers 61 being four in number to correspond with the number of power pneumatics utilized. Each of the pouch chambers 61, is spanned by a pouch 63. Each of the pouch chambers 61 is provided with a duct 64 which is connected by a tube to a hole in the tracker bar 23. Each of the chambers 61 also is provided with a small passage or a bleed hole 65 which

communicates with the vacuum chamber in the valve box hereinafter referred to. The upper portion of the valve housing comprises a block or cap which fits over the base as best shown in Fig. 9, there being suitable sealing material 67 interposed between the cap and base. The cap is provided with an elongated chamber 68 which forms a low pressure air chamber, from which the air is exhausted through a duct 69 communicating with a conduit 70, which is connected directly to the high exhaust, or stated in another manner with the trunk 22 prior to its communication with the governor A. By this arrangement, the air in the chamber 68 is constantly at low pressure. Slidably mounted over the pouch 63 of each of the chambers 61 is a valve 71. Each of said valves includes a stem 72 slidably mounted in a suitable guide bore 73 in the top of cap portion of the valve box, said guide being of greater diameter than the stem 72 and communicating with the chamber 68 and the atmosphere. Each valve has a head 74 adapted to close the bore and is provided with a button 75 at its opposite end adapted to be acted upon by the pouch 63 when the same is vibrated. The top portion of the valve housing is also provided with a plurality of ducts, one of the same communicating with the bore 73 as indicated at 76 in Fig. 9, each of the ducts 76 communicating through a tube with pneumatics in the governor so that when the head of the valve 74 opens the bore 73 atmospheric air will pass along the duct 76 to the corresponding power pneumatic and actuate the same.

The valve arrangement thus far described is generally similar to the primary valve arrangement ordinarily used for admitting atmospheric air, or cutting off the same in connection with various devices of player-pianos, and is of such character that without anything more, the power pneumatics may be controlled by the tubes which lead to the tracker bar. For instance, due to the fact that the chamber 68 is maintained under constant low pressure by the connection 69 with the pump, and due to the bleed holes 65, the pressure beneath the pouches of the valves is likewise reduced. So long as a hole in the tracker bar which communicates with the duct 64 leading thereto, is closed, the valve 74 will be lowered and atmospheric air cut off from the power pneumatics; however, when a hole in the tracker bar is opened so as to let atmospheric air into the duct 64, said air elevates the valve 74 and permits the inflow of atmospheric air through the duct 76 leading to the power pneumatic so as to cause the same to open; and which due to its connection with the movable leaf of the governor operates said governor to vary the intensity of the playing. When the hole in the tracker bar communicating with the duct 64 is again closed, the valve will drop and

seal the bore to the outside atmosphere, and the pressure will be reduced in the power pneumatic due to the constant exhaust from the chamber 68.

5 As above stated, an arrangement of the above character may be utilized for operating the power pneumatics of the dynamic governor, but in this construction it is obvious in order to obtain any accent of the playing 10 over a period of time other than momentary, some means must be provided for continuously admitting atmospheric air for the desired time, and this is usually accomplished by making a slot in the music roll which, as 15 before pointed out, has the disadvantage in that the edge of the sheet is weakened so that the same will not stand up and interferes with proper tracking of the sheet. In order to overcome this difficulty, there is provided a system for actuating the primary 20 valves by small holes in the music roll, the operation being such that when a hole in the music roll registers with the hole in the tracker bar leading to the valve, momentarily opening the valve to atmospheric air, the valve is maintained in position to admit atmospheric air after the music sheet again closes the hole in the tracker bar, the valve being restored to its initial position or cancelled 25 by the registration of a second hole in the music sheet which operates a second valve and restores the first to its initial position.

In carrying out this arrangement, the cap or top member of the valve housing is provided with a channel for each valve, which leads from the bore 73, as indicated at 77, to, and communicates with a central chamber 78, and which is adapted to be placed in communication with a duct 79 which also 30 leads to the chamber 78 and opens through a suitable orifice to a point beneath the pouch 63. Each of the valves 74 is provided with a like arrangement. Mounted at one side of the top portion of the housing or cap is 35 a member 80, said member being provided with a longitudinally extending chamber 81 which is arranged in line with the chambers 78, and fixed over the open end of the chamber 81 is a partition 82 which is provided 40 with a plurality of pouch buttons 83, each one of which is adapted to fit over the mouth of a chamber 78, in one position so as to provide a continuous passage through the ducts 77 and 79 to a point beneath the 45 pouch 63.

In order to provide for the operation of the primary valves automatically so as to actuate the same when once raised to return the same to initial position, there is provided a secondary valve 84. Said secondary valve is adapted to be operated by the pouch 620 which covers the chamber 621, the chamber 621 being in communication with the tracker bar through the conduit 62. The 55 secondary valve 84 is mounted in a bore which

communicates with the vacuum chamber 68 and the atmosphere, and mounted in said bore is a thimble 86 having an enlarged aperture 87 therein, and fixed in the lower end of the bore is a similar member 88 having an enlarged aperture. The secondary valve includes a stem 89 which is mounted for sliding movement in suitable brackets 90, said stem having arranged thereon spaced valve heads 91 and 92, the valve head 92 normally resting under the influence of gravity in such position as to close the opening in the member 88, while the upper valve portion 91 permits atmospheric air to flow through the opening 87 in the upper member. Said air is thence conducted into the chamber 81 by a duct 93, and normally maintains the pouches 83 in such position that the chambers 78 are closed providing a continuous passage for each valve along the ducts 77 and 79 beneath the pouches 63 of the primary valves. When the valve 84 is elevated, the head 91 closes the opening to the atmosphere, and permits the air to be exhausted from the chamber 81, which effects retraction of the pouches 82 and opens the chambers 78. A duct 94 leads from the vacuum chamber 68 to the side of the partition 82 opposite to that presented toward the chamber 81 so that when the air in the chamber 81 is exhausted, the atmospheric air flowing in around the valve stem 72 will be conducted by the duct 94 to the chamber 68.

Although not shown in detail, it will be appreciated that a plurality of additional primary valves may be provided for connection with the crescendo pneumatic in the same manner as the single connection shown is made, so that said pneumatic may be operated in graduated steps in either opening or closing directions, or moved a relatively great extent quickly, depending on the manner in which the tracker bar holes are registered with the valves.

In operation, in playing a piece of music, with the music roll passing over the tracker bar, and it is desired to accent to a certain degree, and for a specified length of time, the music roll will be provided with longitudinally spaced holes arranged a sufficient distance apart to correspond to the duration of time over which the accented portion of music will be played. Assuming that it is desired to accent the music to a relatively small extent, the holes in the music roll will be so located upon the sheet as to actuate the smaller power pneumatic 46. When the advance hole in the music roll registers with the tracker bar, atmospheric air is admitted to the duct 64 of the primary valve shown in Fig. 9, said air passing beneath the pouch 63 so as to elevate the same which in turn elevates the head of the valve 74 so as to admit atmospheric air to the bore 73, which air then flows through the duct 76 to the

power pneumatic 46 and effects certain opening movement thereof, which through its connections with the movable leaf of the governor, spreads said leaf to a certain extent, 5 thereby actuating the knife valve and permitting increased withdrawal of air from the stack to effect the desired accent, it being understood that the striking capacity of one or more pneumatics is identically regulated 10 by the dynamic governor independent of the power pneumatic.

Now it is obvious that if only a single hole of small extent is provided in the music roll that the registry between said hole and the 15 hole in the tracker bar is momentary, and ordinarily the valve 74 would be immediately dropped, cutting off the air from beneath the pouch 63 and from the power pneumatic 46, but due to the provision of the 20 secondary valve arrangement and the associated construction heretofore described in detail this does not occur. On the other hand, atmospheric air normally is given free access to the chamber 81 which causes the pouches 25 83 to close the chambers 78, providing a continuous passage along the ducts 77 and 79 when the valve 74 is raised by the registration of the hole in the tracker bar. The ducts 77 and 79 when the valve 74 is elevated admit 30 atmospheric air to a point beneath the pouch 63 and so maintain the valve elevated and the power pneumatic 46 in communication with atmospheric air. In order to restore the valve 74 to initial position so as to cut 35 off atmospheric air from the power pneumatic 46, the secondary valve arrangement is operated by a second hole in the music roll to admit atmospheric air through the duct 62 beneath the pouch 620, causing elevation of 40 the valve so as to cut off the atmospheric air, and permit the partial exhaustion of the air from the chamber 81, which retracts the pouches 83 opening the chambers 78, and the atmospheric air is then drawn through 45 the duct 94 into the vacuum chamber, cutting off the flow of atmospheric air under the pouch 63, and due to the provision of the bleed hole which is effecting a partial vacuum beneath the pouch, the valve 74 will be 50 dropped and cut off atmospheric air from the power pneumatic 46 through the duct 76. As above stated, each of the power pneumatics has a primary valve connected therewith operating in the same manner as described, and 55 due to the fact that all of said primary valves are arranged in a housing which is maintained under partial vacuum at all times through the conduit 70, operation of the secondary valve through its effect upon the pouches 82 will cancel all of said valves simultaneously, said secondary valve being restored to initial position due to bleeding the 60 atmospheric air from beneath the pouch into the chamber 68.

65 By the above described arrangement, it

will be appreciated that the power pneumatics may be operated in any manner desired, either simultaneously or successively, either in providing a gradually increasing crescendo, or a rapid crescendo effect, and also achieving a sudden or gradual diminuendo as desired.

An important feature of the present invention resides in providing the automatic graduated independently operable power pneumatics which operate upon the reduced air 70 so as to provide for a large range of expression and at the same time insure that the dynamic intensity of one or more notes struck at the same time will be of equal magnitude. 75

While I have herein shown and described what I now consider the preferred manner of carrying out the invention, the same is merely illustrative, and I contemplate all changes and modifications that come within 80 the scope of the claims appended hereto. 85

I claim:

1. In a player-piano, the combination with a pneumatic stack, a pump, and a conduit therebetween; of a governor interposed in said conduit and operable by pressure variations in said stack to automatically control the exhaust; means co-acting with said governor for actuating the same independently of the automatic varying pressure control 90 to effect graduations in the dynamic intensity, said independent means being in the form of power pneumatics connected with said governor; means normally exhausting the air in said power pneumatics; and means controlled by the tracker bar for directly admitting atmospheric air to said power pneumatics to 95 actuate the same.

2. In a player piano, the combination with a pneumatic stack, a pump, and a conduit therebetween; of means interposed in said conduit and operable by variations in pressure in said stack to automatically control the exhaust therefrom; independent means for operating said governor to effect changes 100 in expression by the admission or cutting off of atmospheric pressure; a primary valve arrangement normally maintained in closed position through communication with the exhaust afforded by said pump, said primary 105 valve arrangement being controlled by an opening in the tracker bar to admit atmospheric air to said independent means; and secondary valve means normally admitting atmospheric air to said primary valve means 110 to maintain the latter open after the tracker bar is closed by the music roll, said secondary valve means being operable through the introduction of atmospheric air through said music roll to cut off atmospheric air from 115 said primary valve and restore the same to initial position.

3. In a player piano, the combination with a pneumatic stack, a pump, and a conduit therebetween; of a bellows governor inter- 120

posed in said conduit and operable by variations in pressure in said stack to automatically control the exhaust therefrom; a plurality of power pneumatics disposed within said 5 governor, each of said power pneumatics having one leaf connected to one leaf of the governor, and another leaf connected to the other leaf of the governor, said power pneumatics being sealed from the interior of said 10 governor pneumatic; a plurality of primary valves, each of said valves communicating with one of said power pneumatics, said primary valves being normally maintained in closed position by the exhaust from said 15 pump, said primary valves being selectively operable to control said power pneumatics; and a secondary valve operable through the introduction of atmospheric air to cut off atmospheric air from said primary valves 20 and restore the same to closed position by again connecting them with the exhaust from said pump.

4. In a player piano, the combination with a pneumatic stack, and a pump for exhausting air from said stack; expression means interposed between said pump and said stack, said expression means being operable through the admission of atmospheric air on the one hand and exhaustion of said air on the other 25 hand; and a valve arrangement for controlling said expression means, said valve arrangement comprising a casing having an interior reduced air chamber connected with said pump; a pouch chamber separated from said reduced air chamber by a pouch, said casing having a port communicating with said reduced air chamber; a primary valve normally closing said port and having a portion disposed for co-operation with the pouch 30 covering said pouch chamber; a conduit communicating with said port and adapted to be opened and closed to atmospheric air by said primary valve, said conduit leading to said expression means; a channel leading from 35 said port and opening beneath the pouch of said primary valve; a secondary valve having a pouch chamber communicating with the tracker bar and closed off from said reduced air chamber, said secondary valve communicating with atmospheric air when in 40 one position and with the pump when in another position, said secondary valve normally establishing communication through the channel from said port to beneath the primary valve pouch through the introduction of atmospheric air, and interrupting said communication when said secondary valve is moved to cut off atmospheric air and establish communication with said pump.

45 50 55 60

In witness that I claim the foregoing I have hereunto subscribed my name this 15th day of April, 1926.

JAMES C. ARTHUR.
